UNITED STATES PATENT OFFICE.

HENRY ALBERT VAUGHAN, OF SELMA, ALABAMA.

TOY.

Application filed July 29, 1921. Serial No. 488,444.

To all whom it may concern:

Be it known that I, HENRY A. VAUGHAN, a citizen of the United States, residing at Selma, in the county of Dallas and State of Alabama, have invented certain new and useful Improvements in Toys; and I do hereby declare the following to be a full, clear, and exact description of the invention, such as will enable others skilled in the art to which it appertains to make and use the same.

This invention relates to new and useful improvements in toys, and more particularly to manually operated toys, the main object 15 of the present invention being the provision of a toy of simple construction and including a stationary mannikin having mounted thereon for swinging movement a ladder, normally disposed in a horizontal position 20 with means for raising and lowering this ladder and also a mannikin pivotally supported upon the free end of the ladder and means for imparting movement to said mannikin whereby to cause the same to assume 25 various positions with respect to the latter.

Another object of the invention is the provision of a toy which is extremely simple in construction so that the same can be manufactured at comparatively low cost and the 30 operating means of the toy is so simple so that when any of the parts thereof become broken they can be quickly and readily replaced and the operation is such that the toy can be readily operated by a small child.

With the above and other objects in view the invention consists in the novel features 35 of construction, combination and arrangement of parts hereinafter more fully set forth, pointed out in the claims and shown 40 in the accompanying drawings, in which:

Figure 1 is a side elevation of a toy constructed in accordance with my invention, parts thereof being broken away and illustrated in section and various positions of the 45 toy illustrated in dotted lines;

Fig. 2 is an end elevation;

Fig. 3 is a top plan view;

Fig. 4 is a bottom plan view;

Fig. 5 is a longitudinal sectional view 50 taken on the line 5—5 of Fig. 3;

Fig. 6 is a transverse sectional view taken on the line 6—6 of Fig. 1, and

Fig. 7 is a transverse sectional view taken 55 on the line 7—7 of Fig. 1.

In carrying out my invention, I provide a substantially longitudinal base member gen-

erally indicated by the numeral 1 which can be mounted upon any convenient form of support, the base in the present instance being supported upon two transverse members 60 2 located at each end thereof.

Upon one end of the base 1 are arranged two upright supporting standards 3 having a spacing block 4 arranged between the same, said standards and block being secured 65 to the base member 1 in any suitable manner. Mounted upon the upper end of the standards 3 is a platform 5 and arranged upon the platform approximately centrally thereof is a mannikin, the leg portions 6 of 70 which are rigidly secured to the platform 5 and arranged upon opposite sides of an opening 7. Extending transversely through the upper ends of the leg portions 6 of the mannikin is a shaft 8 upon which the lower 75 end of the body portion 9 of the mannikin is mounted for pivotal movement. Arranged upon the shaft 8 outside of the leg portions 6 are the side rails of a ladder 10 and in order to connect the body 9 of the mannikin 80 to the ladder, the arms 11 of the mannikin are connected to one of the rungs of the ladder as shown at 12 and as the arms 11 are connected to the body 9 by means of the transverse pin 13, the movement of the body 85 of the mannikin will readily impart movement to the ladder.

In order to impart movement to the body of the mannikin 9, a cord or cable 14 is extended through an opening in the body of 90 the mannikin as illustrated in Fig. 5, said cord being secured against movement through the body of the mannikin and from the body the cord extends down over a pulley 15 mounted upon the shaft 16 in the base 1, thence extends to the opposite end of the base 1 and around a pulley 17, said cord being secured to the pulley 17 in any suitable manner whereby the cord will positively move with the rotation of the pulley. 95 The cord 14 then extends under a tightening pulley 18 and is thence returned to the end of the base to which the mannikin is mounted and passed around a pulley 19 and thence from the pulley 19 up to the back portion of 100 the body of the mannikin. It will be noted that the cord 14 is an endless cord and is secured against independent movement to the body of the mannikin and to the pulley 17 so that when the pulley 17 is rotated, the cord will readily pass over the pulleys 15, 18 and 19 and impart movement to the body 105 110.

9 of the mannikin. It will be noted that the lower end of the body 9 of the mannikin is substantially rectangular, presenting two substantially parallel faces over which the 5 cord passes so that when the pulley 17 is rotated in one direction, the body 9 will be forced to move upon the pivot shaft 8 and as the arms 11 of the mannikin are connected to the ladder 10 the ladder may be 10 raised and lowered as shown in Fig. 1 through rotation of the pulley 17. In order to operate the pulley 17 to impart movement thereto, a hand lever 20 is secured to the pulley and projects outwardly therefrom so 15 that by grasping the hand lever 20 when in the position shown in full lines as shown in Fig. 1, and moving the same downwardly to the dotted line position, the body 9 of the mannikin will be moved to the dotted 20 line position shown, thus raising the ladder 10 to an upright position. It will be noted that when the ladder is in a lowered or substantially horizontal position, one of the rungs of the ladder will normally rest upon 25 the upper end of a supporting rod 21 which is mounted upon the base and extends upwardly for the purpose of supporting the ladder.

Mounted for swinging movement with the 30 rung at the outer end of the ladder 10 is a mannikin 22 comprising a body portion having arms and legs pivotally connected thereto in their proper relative positions, the outer ends of the arms being rigidly connected to the outer rung of the ladder and as the outer rung of the ladder is mounted for rotation in the side rails thereof, movement of this rung will impart movement to the mannikin whereby rotation of the rung will cause the mannikin to assume various 35 positions as illustrated in Fig. 1. Mounted upon one end of the rung 23 upon which the mannikin 22 is mounted is a pulley 24 and passed around the pulley 24 is a cord 25 crossed as shown at 26 and then passed over a loose guide pulley 27 and thence extended in opposite directions around a pulley 28 mounted upon the shaft 8. This pulley 28 is provided with a double groove and mounted 40 in the groove opposite the cord 25 is a second cord 29, one end of which extends downwardly and around a guide pulley 30 thence to the opposite end of the base 1 and around an operating pulley 31. After passing 45 around the operating pulley 31 the cord extends beneath a guide pulley 32, thence returns to the opposite end of the base and around a pulley 33 thence upwardly and around the pulley 28 making a complete circuit from the pulley 28 to the pulley 31. The portion of the cord 29 which passes around the pulley 31 is secured to the pulley 50 in any suitable manner so that when the pulley 31 is rotated it will impart movement to the cord 29 rotating the pulley 28, impart-

ing movement to the cord 25 which in turn will rotate the shaft or rung 23 through the medium of the pulley 24. In order to impart movement to the operating pulley 31, a hand lever 34 is connected to the pulley and adapted to be moved in an arc indicated by the arrows whereby to impart movement to the mannikin 22 to cause the same to assume various positions with respect to the ladder 10. 70

By use of endless cords and tightening guide pulleys as described, sufficient frictional resistance is produced to maintain the respective parts normally stationary in any position and at the same time to make the 80 parts respond promptly to any motion of the operative levers so that the toy is susceptible both to unskilled and also to highly skilled manipulation and with the latter can be made to produce a very amusing and entertaining performance closely simulating that of highly skilled acrobats. 85

In order to enclose and guide the cords 29 and 14, a longitudinal piece 35 is mounted upon the longitudinal base 1 and secured to the edges of this top piece 35 are the side portions 36 which are arranged in spaced relation with the sides of the base member 1 in order to provide suitable channels within which the cords 14 and 29 move. 90 In order to enclose the pulleys 17, 18, 31 and 32, a casing is arranged over the pulleys comprising the side walls 36', the end pieces 37 and the central member 38, suitable spaces remaining between the central portion 38 100 and the side walls 36' to permit free movement of the hand levers 20 and 34.

Mounted upon the base portion of the toy and arranged directly beneath the outer end of the ladder when in a horizontal position as shown in Fig. 1, is a supporting bench 39 upon which the mannikin 22 rests when the ladder 10 is in the horizontal position shown. If it be found necessary to enclose the pulleys 30, 33 and 15, a covering member 40 110 may be arranged upon the upper surface of the member 5 and the side portions of said covering may extend down from the edges of the member 5 as shown in Fig. 1 so that the various parts of the operating mechanism will be entirely out of sight. 115

From the above description, taken in connection with the accompanying drawings, it will be readily apparent that I have provided a toy which is extremely simple in construction and can be manufactured and placed upon the market at comparatively low cost. 120

In operating the toy, the ladder 10 and the mannikin 22 may be operated independent of one another. By pulling downwardly upon the hand lever 20, the ladder 10 may be raised to an upright position as illustrated in dotted lines in Fig. 1, then by manipulating the hand lever 34, the mannikin 22 125

may be caused to assume various positions with respect to the ladder, causing the same to imitate an acrobat upon the top of the ladder. Upon releasing the hand lever 20, the weight of the ladder will return the same to its normal horizontal position, as shown in full lines in Fig. 1, and even when the ladder is in this position, the mannikin 22 may be manipulated to assume various positions. The device is so simple that a small child can readily operate the same without any trouble whatever.

I claim:

1. A device of the class described including a base member, a mannikin mounted above one end of the base member, said mannikin having a portion of its body stationary and another portion movable, a ladder member supported by the stationary portion of the body and having engagement with the movable part, manual, controlled, means for imparting movement to the movable portion of the mannikin, whereby to raise and lower said ladder, a second mannikin connected with the outer end of the ladder and independent, manual, controlled, means for imparting movement to the second mannikin whereby to cause the same to assume various positions with respect to the ladder.

2. A device of the class described including a base member, a mannikin supported above the base member, the leg portions of said mannikin being fixed relative to its support, a shaft extending through said leg portions and upon which the body of the mannikin is movable, a ladder having one of its ends movably mounted upon said shaft and connected with the movable portion of the body of the mannikin, flexible means connected with the movable portion of the body of the mannikin whereby to impart movement to the same for raising and lowering the ladder and means for supporting said ladder when in a lowered position.

3. A device of the class described including a base, a platform arranged above the base at one end, a mannikin mounted upon the platform having its legs fixed to the

platform, a shaft extending through the upper portions of the legs and upon which the body portion is mounted for swinging movement, a ladder having one of its ends mounted upon said shaft and having connection with the movable portion of the mannikin, an endless cord extending through the body of the mannikin, a rotatable pulley at the opposite end of the base around which the cord passes and secured thereto, and a hand lever connected with the pulley whereby movement of the hand lever will rotate the pulley and impart movement to the movable portion of the mannikin to raise and lower the ladder.

4. A device of the class described including a base member, a platform arranged above one end of the base member, a mannikin upon said platform having its leg portions affixed thereto, means for pivotally mounting the body of the mannikin between the leg portions, a ladder having one end pivotally connected with the leg portions and connected to the movable body portion whereby movement of the body will raise and lower the ladder, a second mannikin connected with the outer end of the ladder and movable independently with respect to the ladder and first mannikin and independent, manual, controlled, means for operating said mannikins and ladder.

5. A device of the class described including a base member, a platform supported above the base member, a mannikin mounted upon said platform having a movable body, a ladder pivotally supported upon the platform and connected with the movable body, a second mannikin connected with the opposite end of the ladder, and independent, manual, controlled, operating means for imparting movement to the movable portion of the first mannikin whereby to raise and lower the ladder and actuate the second mannikin to cause the same to assume various positions with respect to the ladder.

In testimony whereof I affix my signature.
HENRY ALBERT VAUGHAN.
